UNITED STATES PATENT OFFICE.

ROMAIN LAFRAMBOISE, OF ROCK, MICHIGAN.

CAR-STAKE HOLDER.

1,115,688.

Specification of Letters Patent.

Patented Nov. 3, 1914.

Application filed August 3, 1914. Serial No. 854,646.

To all whom it may concern:

Be it known that I, ROMAIN LAFRAMBOISE, a citizen of the United States, residing at the city of Rock, county of Delta, and State of Michigan, have invented new and useful Improvements in Car-Stake Holders, of which the following is a specification.

My invention relates to improvements in devices for detachably supporting stakes along the side or sides of flat cars, and it pertains more especially to that class of cars which are used for shipping logs. It will be understood that when logs are piled up on the surface of a flat car and against the stakes, that as ordinarily constructed, it is difficult to withdraw the stakes from their sockets when a load is resting against them.

The object of my invention is to provide a device by which all the stakes upon one side of the car, may be simultaneously released from their sockets when the logs which rest against them are free to roll from the platform of the car.

My invention is further explained by reference to the accompanying drawings in which,

Figure 1 represents a side view of a portion of a flat car, showing two of the devices for supporting the stakes. Fig. 2 is a plan view of the mechanism shown in Fig. 1. Fig. 3 is a detail showing the door of one of the stake sockets secured in its closed position, and Fig. 4 is a front view of a hanger shown in Fig. 3.

Like parts are identified by the same reference numerals throughout the several views.

1 represents a portion of the side of one of the cars. It will be understood that while I have shown but two stake holding sockets in Figs. 1 and 2, the number of said sockets may be increased, it being understood that such sockets will be located at short intervals apart along the entire side or sides of the platform of the car. Each of the sockets comprises the two side members 2 and 3, horizontal brace members 4, 4, and 5, 5, and door or front member 6. The door 6 is pivotally supported from the brace members 4 and 5, by the vertical hinge pin 7, which extends down through said brace members and the lugs 8 of said door. 9 is a spiral spring, one end of which is rigidly affixed to said hinge pin 7, and the other end is adapt- ed to bear against said door, whereby said door when released from the retaining member hereinafter described, will be quickly thrown open by the recoil of said spring. Said door 6 is retained in its closed position by the hooks 10, 10, coöperating with the hooks 11, 11 with which they are adapted to engage when said doors are in their closed position. The hooks 10, 10 are formed integral with or rigidly connected to said doors in the ordinary manner. The hooks 11 are both formed integral with the lever 12, and said lever 12 is pivotally connected at its upper end to one of the side members 2 of a post socket by the pivotal bolt 13, while the lower end of said lever 12 is provided with a hook 14, which is adapted to engage the hook 15 of the arm 16. The arm 16 is pivotally supported from the lower side of the car 1 from the hanger 17, by the longitudinal shaft 18. Attached to said longitudinal shaft 18 is a hanger 19, which extends downward and is connected with the horizontal bar 20 by the pivotal bolt 21. The bar 20 is supported in a horizontal position beneath the car by the hanger 22. The hanger 22 is provided with an aperture 23 for the reception of said bar 20. The upper end of said aperture 23 is preferably made sufficiently larger than its lower side to permit said bar 20, when raised from the position shown in Fig. 3, to slide freely through it, while the lower side 23' of said aperture 23 is made narrow, conforming in shape to the rear end of the bar 20, which is made flat and thin to conform to the lower side of said aperture 23, while the front end of said bar 20 is enlarged and is provided with shoulders 24 adapted to engage the sides of the aperture 23' and prevent said bar 20, when in its horizontal position shown in Fig. 1 from moving rearward or toward the right, reference being had to Fig. 3, whereby the arms 16 and 19, hooks 14, 15 and hooks 10, 10 and 11, 11, are normally retained in the position shown in Fig. 3, whereby the door 6 will be prevented from being thrown open and whereby the stakes 26 will be rigidly supported in their vertical position, regardless of any pressure which may be brought to bear against them. When however, it is desirous to release the stakes, the operator has simply to grasp the handle 25 and raise the bar 20 to the upper side of the aperture 23, whereby the shoulders 24 will be brought

out of contact with the sides of the aperture 23', and said bar will be free to move rearwardly in the upper portion of said aperture, when the arm 19 will move to the right, said shaft 18 will be caused to perform a partial revolution, whereby the arm 16 will move downwardly and the hook 15 will be disengaged from the hook 14, thus permitting the lower end of the lever 12 to move forwardly or toward the left, whereby the hooks 11, 11, will be disengaged from the hooks 10, 10, when the door 6 will be thrown open by the action of the spiral spring 9, thereby releasing the stakes 26 from their sockets when the load or a portion of the same will be free to drop of its own gravity from the side of the car.

While I have shown and described a few only of the sockets located upon one side of the platform car, it will be understood that the number of such sockets on one side of the car, may not only be increased, but an additional number of similar sockets may be used upon the opposite side of the car, invention herein being predicated, more especially, upon the mechanism shown and described for holding the front door of the socket in its closed position against the pressure of the stakes and for automatically releasing the stakes when desired, whereby such stakes will be free to drop from their supporting sockets.

Having thus described my invention what I claim as new, and desire to secure by Letters Patent, is—

1. In a device of the described class, the combination with the side of a railway car, of a plurality of stake sockets, each socket comprising a pair of rigid side members, two pairs of brace members connected with said side members, a door pivotally connected with one pair of said brace members, a plurality of hooks for normally holding said door in its closed position, means for manually and simultaneously releasing the retaining hooks of all of said doors, and a spring for throwing all of said doors from their closed to their open position as soon as released from said retaining hooks.

2. In a device of the described class, the combination with the side of a railway car, of a plurality of stake sockets, each socket comprising a pair of rigid side members, two pairs of brace members connected with said side members, a door pivotally connected with one pair of said brace members, a pair of hooks connected with said door, a lever pivotally connected with one of said side members, a pair of hooks connected

with said lever adapted to normally engage the hooks of said door, hooks connected with the lower end of said lever, a longitudinal shaft and arm rigidly connected at one end to said shaft, and provided at its opposite end with a hook, said last named hook being adapted to engage the hook formed upon the lower end of said lever, a releasing arm rigidly connected at one end to said horizontal shaft, a reciprocating bar pivotally connected at one end to the free end of said releasing arm and provided at its opposite end with an operating handle, a hanger provided with an aperture for the reception of said reciprocating bar, means for normally holding said reciprocating bar in a fixed position in relation to said hanger, and means for releasing said reciprocating bar and permitting the same to move freely through the aperture of said hanger.

3. The combination with the respective sides of a railway car, of a plurality of stake sockets, each socket comprising two side members, a pair of brace members, a door hinged to one pair of said side members, a pair of hooks connected with one side of each of said doors, a lever pivotally connected at its upper end to one of said side members, a pair of hooks connected to the upper end of said lever, and adapted to engage the hooks of said door, a hook formed in connection with the lower end of said lever, a horizontal shaft revolvably suspended from the respective sides of the car, an arm rigidly connected with each of said shafts, and provided with a hook adapted to engage the hooks on the lower ends of the lever of the several stake sockets, an additional operating arm connected with each of said horizontal shafts, a reciprocating bar pivotally connected with the free ends of each of said last named arms, a hanger suspended from the respective sides of the platform of the car, each of said hangers being provided with an aperture for said reciprocating bars, and means for releasing each of said reciprocating bars from engagement with its supporting hangers, whereby the retaining hooks of said levers are released from engagement with the retaining hooks of said doors, whereby said doors are free to be thrown open by the recoil of said spring.

In testimony whereof I affix my signature in the presence of two witnesses.

ROMAIN LAFRAMBOISE.
